MECHANICAL POOL TABLE

Filed Sept. 13, 1946

UNITED STATES PATENT OFFICE

2,477,939

MECHANICAL POOL TABLE

Felix Radinsky, Olympia, Wash.

Application September 13, 1946, Serial No. 696,870

2 Claims.

(Cl. 273—3)

1

This invention relates to an improved construction of game ball table which is constructed and arranged to be played in simulation of the well known game of pool, and more particularly constitutes an improvement on my prior application for U. S. Letters Patent, entitled Mechanical Pool Table, filed July 19, 1944, and bearing Serial Number 545,583, now Patent 2,450,613, issued on October 5, 1948.

Whereas in my prior application, each ball after being played is returned either by way of one of the pockets or by a return gate to a locked position beneath the table or playing surface, the present invention permits of the retention on the table, until the completion of a game, of any balls which do not enter into a pocket of the table when initially played, so that subsequently played balls may be utilized similar to cue balls in the conventional game of pool, for driving the balls remaining on the table into the table pockets, thus increasing the score capable of being obtained as a result of special skill of the player and thus rendering the game more interesting and more similar in play to the conventional game of pool.

A further object of the invention is to provide an improved construction of game table possessing the characteristics heretofore described and which is provided with mechanical means for returning all of the balls to a locked position between the completion of one game and the commencement of another.

Various other objects and advantages of the invention will hereinafter become more fully apparent from the following description of the drawing, which illustrates a preferred embodiment thereof, and wherein—

Figure 1 is a perspective view of the improved table;

Figure 2 is a fragmentary perspective view, similar to Figure 1, but showing the table tilted for clearing the balls therefrom;

Figure 3 is a vertical sectional view of the tilting mechanism, taken substantially along a plane as indicated by the line 3—3 of Figure 1 and showing the mechanism in position for supporting the table or playing surface in substantially a horizontal position;

Figure 4 is a similar view taken substantially along a plane as indicated by the line 4—4 of Figure 2 and showing the tilting mechanism in a position for supporting the table at an incline for clearing the balls therefrom;

Figure 5 is a perspective view of one of the pivotal supports for the table top or playing surface, and

Figure 6 is a perspective view of one of the bearing members for the tilting mechanism.

As the present invention relates only to improvements in the table top or playing surface as

2

covered by my prior application for patent, previously referred to, only so much of the mechanical pool table structure has been disclosed as relates to the improved table top. The coin control means, with the ball elevator, the manually manipulated ball receiver from which the balls are played, and the spring loaded cue or ball projecting mechanism has not been illustrated and will not be described in the present application, as these structures have been completely disclosed in my prior application and are intended to be used in conjunction with the improved table top or playing surface.

Referring more specifically to the drawing, a portion of a table frame, designated generally 1, is illustrated in Figures 1 and 2 and includes a pair of side walls 8 and 9 and an outer end portion 10. The end portion 10 includes an upwardly facing glass panel or pane 11, through which an electrically actuated score board, not shown, will be visible. Inwardly of the transparent panel 11, the end portion 10 is provided with an arcuate cushion 12, which is concave and which is provided with two pocket recesses 13, which are located above arcuate recesses 14 which are formed in the bottom of the inner edge of the table part 10.

The playing table or surface proper, designated generally 15 is provided with an arcuate convex edge 16 at its outer end, which is located adjacent and beneath the concave cushion 12 and which is provided with indentations or recesses 17 which register with the recesses 14 to form openings, and which in conjunction with the cushion recesses 13 form ball receiving pockets.

The table or surface 15 is pivotally mounted adjacent its outer edge 16 on a pair of laterally aligned pivots 18. As best seen in Figure 5, each pivot 18 includes a headed pin 19 having a smooth shank portion which is turnably engaged by a loop or barrel portion 20 formed on one end of a plate 21. The pivot pins 19 are provided with opposite tapered threaded ends 22 which are anchored in the frame sides 8 and 9 in a manner to cause the pivot pins 19 to project inwardly therefrom. The plates 21 are connected by fastenings to the underside of the table or surface 15, and adjacent the side edges thereof, to combine with the anchored pivot pins 19, for pivotally mounting the table or surface 15 near its outer end.

The surface 15 is provided with a restricted opposite end having corresponding upstanding side walls 23 which extend to the ends of a concave inner end portion 24 and which converge toward said portion. Portion 24 defines a part of a gate or ball receiver, for a purpose which will hereinafter become apparent. The side walls 23 form integral extensions of the integral upstanding and parallel side walls 25 of surface 15.

which extend from the walls 23 to points adjacent the pivots 18 and which are provided with inwardly extending resilient cushions 26. The cushions 26 are each provided with a recess 27 around an opening 28 in the surface 15. The recesses 27 and openings 28 combine to form additional ball receiving pockets. The cushions 26 at their outer ends are provided with beveled surfaces 29 for exposing additional openings 30 in the table 15 and which combine therewith to form two additional ball receiving pockets. It will be noted that the pockets formed by the recesses 13 and openings 14, 17, recesses 27 and openings 28, and beveled surfaces 29 and openings 30, are all set at an angle to the longitudinal axis of the surface 15 so as to open toward the intermediate part of the arcuate edge 24 of the table 15, or from where the balls are placed in play.

The lower end of the table or surface 15 is supported by a shaft 31 having corresponding offset end portions 32 which are journaled in bearings 33. The bearings 33 each include an elongated bar 34 having apertures for receiving suitable driven fastenings. The bars 34 are secured to the upper edges of the frame sides 8 and 9 and are provided, intermediate of their ends, with transversely disposed grooves 35 in which the shaft portions 32 are journaled.

As seen in broken lines in Figure 1, the frame side 8 is provided with a longitudinally extending outwardly opening recess 36, on the bottom of which a guide 37 is suitably secured in a position transversely thereof. A bar 38 is slidably mounted in the guide 37 for lengthwise movement in the recess 36 and is provided at one end thereof with a pivoted link 39 which may be actuated by the coin control mechanism, or which can be manually actuated, for a purpose which will hereinafter become apparent. A leaf spring 40, which is anchored at 41 in the recess 36, resiliently bears against the upper side of the opposite end of the slide bar 38 to prevent casual movement thereof. The slide bar 38 is provided with an elongated, longitudinally disposed notch or slot 42 to receive a depending terminal 43 of the shaft 31 which is disposed beyond and at right angles to one of the shaft portions 32 and which forms a lever or crank.

The other end of the shaft 31 includes a lever portion 44 which projects downwardly at right angles to the other bearing portion 32 and which terminates in an inturned crank end 45, which is disposed substantially parallel to said last mentioned shaft portion 32. The frame wall 9 is provided with a recess 46 to accommodate the in-turned crank 45 and to receive a headed pin 47, the head 48 of which is apertured to pivotally engage the crank 45. A bracket 49 is secured by fastenings to the frame side 9 and is provided with an outwardly projecting portion having an opening in which the pin 47 is reciprocally mounted and in which it is retained against disengagement by a cross pin or key 50 which extends through the lower portion of the pin 47 and below the outwardly extending portion of the bracket 49. An expansion coil spring 51 is mounted on the pin 47 between the bracket 49 and its head 48 for urging the pin upwardly relatively to said bracket.

From the foregoing it will be readily apparent that the playing balls 52 may be elevated to a level to be propelled across the table or surface 15 by a spring loaded cue after operation of a coin controlled mechanism, all as disclosed in

my prior application for patent, previously referred to. With the shaft 31 in its position of Figure 1 and Figure 3, the table or playing surface 15 will be substantially in a horizontal position, so that the balls 52 may be accurately propelled thereon toward the various pockets, previously described. Any balls 52 failing to enter a pocket, when initially driven by the spring loaded cue will in most instances, after bounding off one or more of the cushions 12 and/or 26 come to rest on the horizontal surface 15. Subsequently propelled balls 52 can then be utilized in a manner similar to a cue ball for attempting to pocket the balls remaining on the surface 15, but differing from the conventional cue ball, in that the player also attempts to cause the ball, driven by the spring loaded cue, to also enter one of the pockets. After all of the balls have been propelled by the spring loaded cue, certain of the balls will have passed downwardly through openings 14, 17, or through the openings 28 and/or 30 to be returned by gravity along the bed of the table to a location to be again raised to a playing position by the elevator, after the coin controlled mechanism has again been operated, all as disclosed in my prior application, previously referred to. The remaining balls 52 which are left on the surface 15 are returned to the bed of the game board and to a position to be reused when the elevating mechanism is again actuated, by a movement from right to left of the slide actuating bar 38, as seen in Figure 1. As the bar 38 is moved from right to left, the inner end of the notch 42 will engage and rock the lever 43 in a clockwise direction to swing the shaft portion 31 in a clockwise direction on the pivot 32 through an arc of substantially ninety degrees. This will cause the crank 45 to be swung in the same direction and from its position of Figure 3 to its position of Figure 4. The crank 45 and lever 44 will thus be swung across the dead center of the pivot points 32, 45 and 49, so that the spring 51 will retain the shaft 31 in its position of Figure 4, until the operating bar 38 is moved in the opposite direction or from left to right. When this occurs, the outer end of the notch 42 will engage and swing the lever 43 in a counter-clockwise direction, as seen in Figure 1, for returning the parts to their original positions of Figure 1 and Figure 3 and for causing the pivot 45, 48 to again cross its dead center position, so that the spring 51 will act to hold the shaft 31 in its position of Figure 3, to thus support the table or surface 15 in a horizontal position. It will be readily obvious that when the table is tilted by the shaft 31 being moved to its position of Figure 2, as previously described, that the balls 52 resting on the surface 15 will roll toward and off of the edge 24 and onto the table bed below. The slide bar 38 may be arranged to be suitably actuated by movement of the coin controlled mechanism or may be manually actuated directly from a position externally of the game board apparatus upon its being suitably released by coins being placed in the coin controlled mechanism.

Various modifications and changes are contemplated and may obviously be resorted to, without departing from the spirit and scope of the invention as hereinafter defined by the appended claims.

I claim:

1. A game board playing surface actuator, comprising a rod having spaced portions adapted to be journaled in a game board frame, said rod having an offset portion between said journaled

portions adapted to engage beneath and support an end of a playing surface which is pivotally mounted adjacent its opposite end in said frame, said rod having a down turned crank portion at one end thereof, and a manually actuated member reciprocally mounted relatively to said frame and engaging said down turned crank portion for

rocking the intermediate portion of said rod for raising or lowering the end of the playing surface supported thereby.

2. A game board playing surface actuator as in claim 1, said rod having a crank portion at its opposite end, and a spring biased element pivotally connected to said last mentioned crank portion and adapted to be pivotally mounted relatively to the frame, said spring biased element being swingable across a line joining its pivot with the journals of said rods when the inter-
